HIGH FREQUENCY TRANSMITTING
CIRCUIT

George L. Usselman, Port Jefferson, N. Y., assignor to Radio Corporation of America, a corporation of Delaware

Application June 22, 1932, Serial No. 618,607

11 Claims. (Cl. 250—17)

This invention concerns an improved coupling arrangement for coupling the output of a radio transmitter to a utilization circuit, such as a transmission line or an antenna system.

5 Radio transmitters are frequently provided with two or more antenna systems for enabling the transmission of signals efficiently on more than one wave length. It is customary in transmitters which are adapted to operate on two or 10 more frequencies to use a transmission line and antenna for each frequency and to provide individual variable arrangements for adjusting the coupling of each line. Heretofore, inductive coupling has been avoided in such systems due to the 15 great difficulty which has been experienced in combining more than one inductive coupling coil to the single output of the transmitter. Since each of the transmission lines is adapted to function most efficiently on a frequency which differs 20 greatly from those utilized by the other transmission lines, it has been found that a common coupling coil which is correct for only one particular frequency and not correct for other frequencies, does not lend itself readily to the efficient design of multi-frequency radio transmitters. For these reasons, it has been the practice 25 in the past to use conductive coupling. Conductive coupling, however, has certain disadvantages, such as causing the transmission line and antenna to radiate second harmonic and push-push parasitic frequencies. These parasitic frequencies occur because the attached transmission line supplies a circuit in addition to the regular oscillating circuit.

30 In accordance with the present invention, the foregoing disadvantages are entirely overcome by the provision of a single inductance coil coupling arrangement for all frequencies and all antennae.

Several features of the present invention reside 35 in the variable reactance circuits for adjusting the couplings of the individual transmission lines and for efficiently eliminating second harmonic energy in the lines and antenna systems.

The invention is described more in detail in the 40 following description accompanied by drawings, in which

Figure 1 illustrates a single inductance coil coupling arrangement in accordance with the present invention which is adapted to selectively 45 connect one of a plurality of transmission lines to the output circuit of a radio transmitting system; and

Figure 2 illustrates a modification of the circuit of Figure 1.

50 Figures 3, 4 and 5 illustrate preferred embodiments

ments of the present invention. These include impedance changing circuits for the elimination of undesirable second harmonic energy from the transmission lines and antenna systems.

Figure 6 illustrates a further embodiment for eliminating undesirable second harmonic energy.

Figures 7 and 8 illustrate the present invention as applied to a single frequency transmitter or power amplifier stage utilizing only one antenna.

Referring to Figure 1, there is shown a multi-frequency radio transmitting system which is adapted to transmit signals on either of two frequencies over antenna systems 1 and 2. The radio transmitter is indicated diagrammatically in box 1 and may comprise a conventional type of push-pull power amplifier stage with which there is associated an output coil or tank circuit 2. Since the transmitting circuit forms no part of the present invention and is of a type that is well known in the art, no detailed description of the transmitter will be given herein. A single coil 3 is adapted to inductively couple tank circuit 2 to any one of the antenna systems 1 and 2 through switch 4. Connected to the center point of coil 3 is a high resistance element 5 which also connects with the plate supply lead as shown in the drawings. The purpose of this resistance will be described later. Serially connected in the transmission lines 7 and 8 and extending from 30 switching mechanism 4 to the antenna systems are a plurality of blocking condensers 6, 6 of negligible impedance to the high frequency currents, which prevent direct current from the positive source of plate supply from entering the 35 antenna circuits proper.

High frequency radio energy is fed from tank coil 2 by means of the electromagnetic coupling to coil 3, through switch 4 to one of the transmission lines 7 and 8. This switch may be thrown either up or down to select the desired transmission line and antenna system.

For effecting proper coupling for all transmission lines and antennae at their operating frequencies coupling coil 3 is adjusted to give correct coupling for that transmission line and antenna which takes the most power on a particular frequency and, consequently, requires the closest coupling. In most cases, this amount of coupling would be too much for correct operation of the system on other frequencies over other transmission lines and antennae. To obviate this difficulty, adjustable impedance coils 9 and 10 are provided in transmission line 8 to reduce the coupling and to cause the line to take less power.

These impedance coils are then adjusted to effect the desired degree of coupling. In this manner, the advantages of inductive coupling are obtained by the use of only a single coupling coil for a plurality of transmission lines and antenna systems.

Resistor element 5 is arranged to maintain coupling coil 3 at the direct current plate potential to prevent arcing from the plate tank coil 2 to the coupling coil 3; a condition which would otherwise occur due to leakage across the transmission line blocking condensers 6, 6. If it were not for this connection to the plate supply such arcing would be recurrent as the charges on the coil leak off through the condensers 6, 6 and tend to cause the coil to assume a ground potential.

Figure 2 shows an arrangement wherein a condenser 11, preferably variable, is utilized across transmission line 11 and coupling coil 3 for adjusting the coupling. In this circuit, coupling coil 3 is arranged to work into a lower impedance and condenser 11 is utilized to increase the coupling to any desired degree.

In Figure 3 there is shown an arrangement which has been used to good advantage in eliminating undesirable second harmonic energy in the transmission line and antenna. To accomplish this, a balanced or "split" capacity type of condenser 21 is connected to ground at its center point through lead 12. It should be noted that this connection does not affect the fundamental energy in the line which operates push-pull, that is, in phase opposition, whereas all even harmonic energy, noticeably the second harmonic, will be grounded because of the push-push or cophasal effect on the transmission line. If desired, an inductance 13 may be utilized in the connection 12 to tune out the capacitive impedance of condenser 21 for the second harmonic frequency so as to make the effective impedance to ground for the second harmonic energy very low. In this way, practically all the second harmonic energy present in the transmission line is by-passed to ground.

Another method of reducing the undesirable second harmonic energy is to ground the center point of coupling coil 3 through a large capacity blocking condenser 14, as shown in Figure 3 of the drawings. This condenser should have a sufficiently high value to withstand the plate voltage of the stage to which coil 3 is coupled.

In Figures 4 and 5 are shown the preferred arrangements embodying the principles of the present invention. These embodiments utilize an improved coupling arrangement comprising both the coils 9 and 10 and the balanced or "split" capacity type condenser 21 to effect the desired change in transmission line impedance facing coupling coil 3. Coils 9 and 10, together with condenser 21, may be called an impedance changing circuit, an important characteristic of which is its ability when properly adjusted to present to the coupling coil 3 the desired impedance at unity power factor. In other words, the load presented to the transmitter at the operating frequency is purely resistive. The adjustment of the coupling arrangement shown in Figures 4 and 5 is somewhat different from that described for Figures 1, 2 and 3. The coil 3 in Figures 4 and 5 may be constructed to provide correct coupling for either one of the transmission lines and antennae while impedance changing circuits (coils 9 and 10 and condenser 21) may be adjusted to provide correct coupling for the remaining transmission lines and antennae. Again, coupling coil 3 may be made to have any convenient or desir-

able size and the correct degree of coupling may be provided for each transmission line and antenna by proper adjustment of an impedance changing circuit (coils 9 and 10 and condenser 21) in each transmission line.

Switching elements 15 are used for grounding the idle antenna transmission line. It has been found that the harmonic radiation from the transmitter is thus greatly reduced by grounding in the power amplifier that transmission line which is not in use at the particular time of transmission. Switches 15, 15, it should be noted, are short circuiting switches and made to ground the transmission lines on the antenna side of the D. C. blocking condensers 6, 6. These ground switches may be connected to the frame of the transmitter or to any point which is substantially at ground potential.

In Figure 5 variable impedance coils 9 and 10 are shown connected between balanced condenser 21, which is connected across the transmission line, and the antenna, whereas in the other figures the variable impedance coils are shown between coupling coil 3 and the balanced condenser 21. The former manner of connection is desirable for decreasing the coupling between the antenna system and the coupling coil, whereas the latter manner is desirable for increasing the coupling.

It should be noted that Figures 4 and 5 also include the connection of the middle element of variable condenser 21 to ground through the variable inductance coil 13 and the connection of the midpoint of coupling coil 3 to ground for high frequencies through the by-pass condenser 14, for the purpose of reducing harmonic radiation.

Figure 6 illustrates a further arrangement for eliminating second harmonic energy in the transmission line and antenna. The circuit shown consists of two connections each having a length of one-fourth of the fundamental wave length extending from ground to points 16 and 17 on each of the two wires 1 respectively, which are the same distance from coil 3. These connections are one-quarter wave length long for the fundamental frequency and therefore offer a high impedance to currents of this frequency, but are one-half wave length long for the second harmonic frequency and present very low impedance to ground for currents of this latter frequency, thus eliminating energy of this harmonic frequency from the transmission lines and antennae. If desired, coils which are effectively a quarter wave length long for the fundamental frequency or a half wave length long for the second harmonic frequency may be used instead of the one-quarter wave length straight wires for eliminating the second harmonic energy. If standing waves exist cophasally on the transmission line, points 16 and 17 should be located at the high potential points on the reflected second harmonic wave for more effective elimination of the second harmonic energy.

It should be noted that the system shown in Figure 6 may be used instead of the harmonic reducing circuit 12 in the other figures, and may readily be utilized in a single frequency transmitter having only one transmission line and antenna wherein it is inconvenient to use a coupling coil of a certain size and shape to give correct coupling. In such case, it would be possible to use a coupling coil of a very convenient size and shape and, by the use of impedance coils

in accordance with the present invention, adjust the coupling to the required degree.

Figures 7 and 8 illustrate a modified form of the present invention as applied to a single frequency transmitter having one antenna system, or as applied to a multi-frequency transmitter having a power amplifier stage for each frequency and antenna. In the figures shown, both power amplifiers of a transmitter, of course, may be energized at different times from a single exciter circuit. Figure 7 shows the arrangement of the impedance changing circuit 9, 10, 21, for presenting a low impedance to the coupling coil 3. Such an arrangement is adapted to increase the coupling between the transmitter and the antenna system. Figure 8 shows the arrangement of the impedance changing circuit for presenting a high impedance to coupling coil 3. The latter coupling arrangement decreases the coupling between the transmitter and the antenna.

The coupling arrangements shown in Figures 7 and 8 are desirable for reducing harmonic radiation and for stopping parasitic oscillations and also for enabling the use in the transmitter of a rigidly fixed coupling coil without fractional turns. This also allows the use of a convenient or desirable size of coupling coil regardless of coupling since correct coupling can be obtained by proper adjustment of the impedance changing circuit (coils 9 and 10 and condenser 21).

I claim:

1. A wireless transmitter adapted to operate on either of two or more frequencies having, in combination, an amplifier stage, a transformer having a primary winding and a secondary winding, said primary winding comprising the output of said amplifier stage, a first two wire transmission line and a second two wire transmission line, condensers in each wire of said two transmission lines, switching mechanism for selectively connecting either one of said transmission lines to said secondary winding of said transformer, and a balanced variable condenser arrangement connected across the wires of one of said transmission lines for adjusting the impedance thereof, the effective midpoint of said condenser arrangement being grounded.

2. A wireless transmitter adapted to operate on either of two or more frequencies having, in combination, an amplifier stage, a first two wire transmission line and a second two wire transmission line, condensers in each wire of said two transmission lines, a single coil inductively coupled to the output of said amplifier stage, switching mechanism for selectively connecting either one of said transmission lines to said single coil, and variable reactance means associated with one of said transmission lines for adjusting the coupling thereof, a connection from the mid-point of said inductively coupled single coil to ground, and another connection from the effective center point of said variable reactance means to ground.

3. A wireless transmitter having, in combination, an amplifier stage, a first two wire transmission line, and a second two wire transmission line, condensers in each wire of said two transmission lines, a single coil inductively coupled to the output of said amplifier stage, switching mechanism for selectively connecting either one of said transmission lines to said single coil, a variable condenser connected across the wires of one of said transmission lines for adjusting the coupling thereof, a connection from the mid-point of said

inductively coupled single coil to ground, and another connection from the effective center point of said variable condenser to ground, said last connection including a variable inductance to tune out the capacitive impedance of said variable condenser for the second harmonic frequency of the fundamental working wave for which said one transmission line is tuned.

4. In combination, a wireless transmitter including a power amplifier stage having an output circuit, a single coil inductively coupled to said output circuit, a connection including a capacity from the mid-point of said single coil to ground, a first antenna circuit and a second antenna circuit, means for selectively associating said single coil in operative relation with either of said two antennas, condensers serially connected in the lines of said first and second antenna circuits, and variable reactance means in one of said antenna circuits for adjusting the coupling of said one circuit to said single coil.

5. In combination, a wireless transmitter including a power amplifier stage having an output circuit comprising a coil whose mid-point is capacitively connected to ground, another coil inductively coupled to said first coil and a capacitive connection from the mid-point of said second coil to ground, a first transmission line and a second transmission line, switching mechanism for selectively connecting said second coil with either one of said two transmission lines, and variable reactance means in one of said transmission lines for adjusting the coupling of said one transmission line to said second coil.

6. A wireless transmission system as defined in claim 5 including a resistor connected between the mid-points of said two coils.

7. A radio frequency transmitter having, in combination, an output circuit including a first inductance coil, a plurality of transmission line systems adapted to operate on different frequencies, a second coil inductively coupled to said inductance in the output circuit, switching mechanism for selectively connecting said second coil to any one of said transmission line systems, and means for maintaining the mid points of both coils at substantially the same direct current potential.

8. A radio frequency transmitter having, in combination, an output circuit including an inductance, a two wire transmission line, an antenna, a single coil inductively coupled to said inductance in said output circuit and connected to one end of said line, the other end of which is connected to said antenna, adjustable coupling means comprising a variable reactance coil in each wire of said line, a balanced variable condenser across said line, and a connection from the middle of said balanced condenser to ground.

9. A transmitter as defined in claim 8 including a variable reactance coil in said connection for tuning the capacity of said condenser.

10. In combination, a radio frequency transmitter having an output circuit, a coupling coil inductively related to said output circuit, an antenna having a two conductor transmission line connecting said antenna with said coupling coil, an impedance changing circuit having an inductive reactance coil connecting one of said transmission line conductors to one terminal of said coupling coil, a second inductive reactance coil connecting the second transmission line conductor to the other terminal of said coupling coil, and a capacitive reactance condenser having a central element connected to ground through a

tunable reactance coil for reducing harmonic radiation, the terminals of said condenser being arranged in shunt to said transmission line conductors, said reactance coils and condenser of said impedance changing circuit being capable of arrangement and adjustment to transform at the operating frequency the transmission line impedance in such manner as to present to the coupling coil and transmitter output circuit a load of pure resistance and of optimum value having minimum harmonic radiation.

10 11. In combination, a wireless transmitter in-

cluding a power amplifier stage having an output circuit, a single coil inductively coupled to said output circuit, a first antenna circuit and a second antenna circuit, means for selectively associating said single coil in operative relation with either of said two antennas, condensers serially connected in the lines of said first and second antenna circuits, and variable reactance means in one of said antenna circuits for adjusting the coupling of said one circuit to said single coil. 10 5

GEORGE L. USSELMAN.
